JOSEPH A. PELIZZONI, OF ALLENTOWN, PENNSYLVANIA, ASSIGNOR TO INTERNATIONAL MOTOR COMPANY, OF NEW YORK, N. Y., A CORPORATION OF DELAWARE.

METHOD OF AND APPARATUS FOR BENDING AXLES AND THE LIKE.

Application filed February 23, 1922. Serial No. 538,496.

This invention while applicable to the bending of metal parts generally will find its greatest usefulness in connection with the bending of axles of automobiles which, for 5 reasons well known, are given a permanent camber or set. Heretofore, this bending has been done by hand and in a slow tedious expensive manner requiring considerable skill for its successful practise. In this hand 10 method it has been found humanly impossible to insure a uniform camber throughout the axle so that the corresponding sections thereof at opposite sides of the mid point will have the same relative positions. This 15 lack of uniformity has resulted in the axle spindles and the wheels thereon being set in improper relation. The object of the present invention is to provide an improved method of and fixture for bending axles and 20 the like and imparting to them a uniform camber at opposite sides of the mid point. More particularly, the invention is concerned 25 with an improved fixture in which axles of different sizes may be placed quickly in such relation to the bending devices as to facilitate the imposition of bending 30 stresses which will impart the required camber. Further, the invention is concerned with a fixture in which are employed 35 gauges designed to indicate accurately to the operator just when the predetermined 40 camber has been given to the axle. Still another object of the invention is to incorporate in such a fixture interchangeable 45 supports for the axle whereby the supporting blocks may be adapted to receive axles of different sizes and yet support them in desired relation to the indicating gauge 50 plugs and the bending devices.

In accordance with the improved method it is proposed to support the axle at points remote from its center and impress bending stresses on its mid section whereby the camber imparted at opposite sides of the 55 mid section will be uniform by reason of the confinement of the ends. In the improved method the extent of camber is indicated by deflection of free portions of the axle with reference to fixed gauge points in the fixture in proximity to the middle or the ends, respectively. The method described may, of course, be practised successfully with means other than those illustrated herein, although the fixture disclosed has been found in prac-

tise to be satisfactory for the desired purpose. In this improved fixture V-blocks, adjustable longitudinally of the fixture are provided for the support of the ends of the axle, these blocks having mounted removably therein interchangeable bearing plugs 60 of different sizes by which axles of different sizes may be supported on the same center line. Axial displacement of the axle is prevented in the improved fixture by means of adjustable end stops. The degree of deflection of the axle is indicated by fixed gauge points which the axle touches when bent. The bending device proper, in the preferred form, comprises a hand wheel on the spindle of which is carried a presser block adapted to engage the side of the axle. Yielding seats are provided adjacent to the mid section of the axle to resist turning 65 stresses to which the axle may be subjected during bending.

The invention will be described in greater detail with reference to the preferred embodiment illustrated in the accompanying drawings, wherein:

Fig. 1 is a view in plan of the improved machine showing its adaptation to the bending of the axles for motor vehicles.

Fig. 2 is a view in front elevation thereof, parts being broken away in the interest of 85 clearness.

Fig. 3 is a view in transverse section taken through the bending devices and on the plane indicated by the line 3-3 of Fig. 1 and looking in the direction of the arrows.

Fig. 4 is a view in transverse section taken through the base of the fixture and on the plane indicated by the line 4-4 of Fig. 1 and looking in the direction of the arrows.

Fig. 5 is a view in end elevation of the fixture.

Fig. 6 is a view in plan showing somewhat modified means for indicating the amplitude of the bend by gauge points.

Fig. 7 is a view in transverse section through the machine shown in Fig. 6 and taken on the plane indicated by the line 7-7 of Fig. 6 and looking in the direction of the arrows.

Fig. 8 is a view in transverse section taken along the plane indicated by the line 8-8 of Fig. 6 and looking in the direction of the arrows and showing modified clamping devices for the V-blocks.

The claims of the present application are intended to cover the improved method of bending axles and the like as disclosed herein as well as the machine for practising the method, inasmuch as it will be clear as the description proceeds that the improved method may be practised by other machines than that disclosed in the drawings. However, for convenience in this description, the 10 preferred embodiment of a machine for bending the axles of motor vehicles will first be described with some degree of particularity in order that the method in its broader aspects may be more readily understood.

The elements of the improved machine may be mounted on any suitable base illustrated herein as I-beams *a*. On the base are secured in spaced relationship suitable devices for supporting the axle *b* adjacent to its free ends, these supporting devices in the illustrated embodiment being represented as V-blocks *c* having hinged clamping caps *c*¹ which may be held releasably in desired relation to the blocks by means of swinging bolts *c*² hinged to the blocks and adapted to be engaged with the caps *c*¹ by means of lock nuts *c*³ threaded thereon. In the blocks *c* and caps *c*¹ are removably carried bearing 30 plugs *d* the sizes of which are appropriate to the axle being bent and which are in spaced relationship, and constitute self-aligning supports for the axle. The bearing faces of these plugs *d* may be slightly spherical. 35 Pairs of such plugs may be mounted in complementary relation, as indicated in plan in Fig. 1.

Adjacent to the mid section of the fixture and to the mid section of the axle, when in place, may be provided two yielding supports for the axle formed as plungers *e* which float on springs *e*¹ adjustably seated on threaded plungers *e*². By adjustment of the threaded plungers *e*², it is evident, as viewed in Fig. 2, 40 that the initial elevation of the plungers may be determined as well as the tension on the springs *e*¹. These spaced seats *e*, of course, while affording a yielding support for the axle *b*, adapt themselves to its elevation as 45 determined by the V-blocks *c* but have the effect of resisting twisting stresses impressed on the axle during the bending operations. At about where the mid section of the axle *b* is found when the latter is in its supporting 50 blocks are mounted in the fixture the bending devices proper. These include a threaded shaft *f* on one end of which is an operating hand wheel *f*¹ and on the other end of which is a presser block *f*² the faces of which may 55 be curved for easy engagement with the side of the axle.

At the extreme opposite ends of the base beams *a* are secured plates *g* on which are supported standards *g*¹ adapted to slide longitudinally of the plates *g* and to be secured

adjustably in place by means of bolts *g*² and lock nuts *g*³ thereon. The heads of these bolts *g*² are disposed in under-cut ways *g*⁴ formed in the appropriate sections of the base plates *g*. In the end wall of the standards *g*¹ are threaded stop screws *h* which may be adjusted to engage the opposite ends of the axle *b* and hold it against axial displacement during the bending operation. In the sides of the standard *g*¹ may be supported removably gauge plugs *i* which have tapered ends resting in proximity to the axle spindles *b*¹. The amount of taper of the ends of the gauge plugs *i* correspond to the degree of camber to be given to the axle. In the preferred practise, the blocks will be so disposed with respect to the spindles *b*¹ that the taper of the faces will show daylight between the plugs and the spindles before the bending operation and this daylight will be lost when the spindles have been deflected by bending to an amount corresponding to the taper of the plugs *i*, that is, to an amount corresponding to the camber to be given to the axle. The plugs *i*, as heretofore stated, may be removed and replaced in the standards *g*¹ by plugs having their ends formed with some other taper, depending upon the predetermined camber to be given to the particular axle to be bent.

It may be desirable for axles of different lengths to change the initial setting of the standards *g*¹, and for that reason the bolts *g*² and nuts *g*³ are provided for convenient adjustment thereof. In the same way, it might be desirable to change the initial setting of the V-blocks *c* and to that end these blocks are set in gibs *k* which themselves may be seated in the base plates *g* with capacity for angular adjustment without longitudinal or lateral displacement. To this end, the gibs *k* have circular bosses *k*¹ formed on their under face which seat in recesses *g*⁵ of corresponding form in the upper faces of the base plates *g*. Bolts *k*² passing through the gibs *k* and the base plates *g* provide convenient securing means for maintaining the gibs *k* releasably in adjusted relation to all of the parts.

In practice, the hand wheel *f*¹ will be revolved until the curved presser block *f*² is retracted sufficiently to permit an axle to be placed on the yielding seats *e* with its ends resting in the V-blocks *c*. The bearing plugs *d* within the V-blocks *c* and their caps *c*¹ will be of such size as to support the particular axle to be bent at the proper height with respect to the presser block *f*². The cap *c*¹ will be thrown over the axle and clamped in place by the lock nut *c*² and bolt *c*³ after the initial setting. The threaded stops *h* will be turned up to bear lightly against the ends of the axle and thereby hold it against axial displacement. Suitable gage plugs *i* having a taper corresponding to the

predetermined camber to be given to the axle will have been mounted in the standards g^1 . The axle when placed in the improved fixture will have been heated adjacent its mid section so that bending stresses may be effectively imposed thereon and a permanent set be held as the cooling proceeds. The hand wheel f^1 when set up on will force the block f^2 against the mid section of the axle b and thereby give the axle a uniform camber from the mid point outwards, the V-blocks adjacent to the ends of the axle insuring a corresponding movement of corresponding sections at opposite sides of the mid point. The operator will observe the spindles b^1 approaching parallelism with the tapered faces of the gage plugs i and when this parallelism is attained will know that the predetermined camber is in the axle. When this desired camber has been gotten, of course, it is necessary to have it permanently retained. To ascertain this, the operator may retract the presser block f^2 slightly and observe whether the relation between the spindles and the gage plugs i is maintained. The feel of the wheel f^1 will also indicate to his practised hand whether there is any springiness in the axle or whether it has taken a permanent set with the camber in it. After this permanent set has been secured the presser block f^2 is retracted and the caps c^1 thrown back to permit the removal of the axle.

In Figs. 6 and 7 are shown modified means of gauging the camber of the axle during the bending which, under some conditions of use, may be preferable to those heretofore described. For instance, it is true that the highest degree of accuracy can only be secured with the gauge plugs i when a skilled operator is employed. In the construction shown in Figs. 6 and 7 the base A of the machine carries thereon a fixed bracket A^1 opposite the bending screw F^1 for the support of an adjusting screw A^2 . In gauging the camber of the axle it is proposed to adjust the screw A^2 at such a distance from the axle (before the bending) that a gauge I of predetermined thickness will rest between the axle when in position to be bent and the end of the screw A^2 . When this adjustment of the screw A^2 has been made the bending operation will be carried on in the manner hereinbefore described until the axle has been forced against the end of the screw A^2 when the operator will find that the predetermined amount of camber has been imparted to the axle. Obviously, gauge plugs of different thicknesses may be used and axles of varying breadths may be given the same camber without variation so long as the same gauge is employed. No particular skill is required and the results are perhaps more invariable.

In the modified devices illustrated in Fig.

8 the cap C^1 of the V-block C is clamped in place to hold the axle by means of a link C^2 pivoted to the block C and cam handle C^3 pivoted to the link and co-operating with the cap C^1 to clamp the cap releasably. This construction affords a convenient and very rugged retaining means for the cap C^1 .

The improved method, as will now appear, clearly resides in the bending of axles and the like by a suitable fixture rather than by hand and consists in heating the mid section of the axle, confining its ends and applying bending stresses to the heated mid section and maintaining such stresses until the axle has cooled sufficiently to hold a permanent camber. The method further consists in ascertaining the permanency of this camber by alternately applying and relieving the stress on the heated section of the axle and observing the effects both through the feel at the time the stress is relieved and through variations in daylight showing between the plugs i and the spindles b^1 . Another incidental step in this method is the support of the axle on self-adapting supports and the clamping of the axle against axial displacement.

As has been indicated before other devices not particularly described herein may find such embodiment as to enable the improved method to be practised but such other fixtures are to be considered within the scope of the invention so far as corresponding elements are employed for the purpose of producing and resisting the stresses in the manner particularly described.

I claim as my invention:

1. The method of bending axles and the like which consists in heating the mid section, placing it in adjustable supports near the ends thereof, applying bending stresses to the mid section thereof until the axle is indicated by suitable indicating devices to have assumed the predetermined camber and alternately relieving and applying the said bending stresses to the mid section until it is found to be free from elasticity and the ends remain in fixed relation to the indicating devices.

2. A fixture for bending axles and the like including V blocks having interchangeable bearing plugs of different sizes to support axles of different sizes on the desired center line, yielding means to afford support for the axle adjacent to the mid section, and adjustable stops to limit axial movement of the axle.

3. A fixture for bending axles and the like including yielding seats for the mid section of the axle, V-blocks having adjustable bearings for axles of different sizes, removable gauge plugs having tapered faces co-operating with the axle spindles to indicate the predetermined camber, a presser block engaging the axle adjacent the mid section,

4
and manual means to force the block against the axle.

4. In a machine for bending axles and the like, V-blocks to support the axles near the ends, gibbs in which said supports are slidably carried for longitudinal adjustment, means to support the gibbs pivotally while maintaining them against longitudinal and lateral displacement, end stops for the axles, and means to support said end stops adjustably so that they may be moved toward and away from the axle.

5. In a machine for bending axles and the like, the combination of a frame, blocks for supporting the axle intermediate its ends, means for mounting the blocks on the frame so that they can turn about a vertical axis, bearing plugs the sizes of which are appropriate to the size of the axle being bent, car-

ried by said blocks and engageable against the axle, and means for applying pressure to the axle between the supporting blocks.

6. In a machine for bending axles and the like, the combination of a frame, blocks for supporting the axle intermediate its ends, means for mounting the blocks on the frame so that they can turn about a vertical axis as well as be adjusted longitudinally, means for preventing axial movement of the axle, means for supporting the axle vertically where the bending forces are exerted, means for exerting a bending force at the middle of the axle and means for gaging the deflections.

This specification signed this 17th day of February, A. D. 1922.

JOSEPH A. PELIZZONI.
